(57) **CLAIM**

The ornamental design for a montessori toy set as shown and described.

DESCRIPTION

FIG. 1 is a front, right and top perspective view of a montessori toy set, showing my new design;

FIG. 2 is a front, right and top perspective view of the Barrel of the montessori toy set;

FIG. 3 is a rear, left and bottom perspective view of FIG. 2;

FIG. 4 is a front, right and top perspective view of FIG. 2;

FIG. 5 is a front elevation view of FIG. 2;

FIG. 6 is a rear elevation view of FIG. 2;

FIG. 7 is a left side elevation view of FIG. 2;

FIG. 8 is a right-side elevation view of FIG. 2;

FIG. 9 is a top plan view of FIG. 2;

FIG. 10 is a bottom plan view of FIG. 2;

FIG. 11 is a front, right and top perspective view of the Lid 1 and Barrel of the montessori toy set of FIG. 1 in an alternate configuration;

FIG. 12 is a front, right and top perspective view of the Lid 1 of the montessori toy set;

FIG. 13 is a rear, left and bottom perspective view of FIG. 12;

FIG. 14 is a front elevation view of FIG. 12 FIG. 15 is a rear elevation view of FIG. 12;

FIG. 15 is a rear elevation view of FIG. 12;

FIG. 16 is a left side elevation view of FIG. 12;

FIG. 17 is a right-side elevation view of FIG. 12;

FIG. 18 is a top plan view of FIG. 12;

FIG. 19 is a bottom plan view of FIG. 12;

FIG. 20 is a front, right and top perspective view of the Lid 2 and Barrel of the montessori toy set of FIG. 1 in an alternate configuration;

FIG. 21 is a front, right and top perspective view of the Lid 2 of the montessori toy set;

FIG. 22 is a rear, left and bottom perspective view of FIG. 21;

FIG. 23 is a front elevation view of FIG. 21;

FIG. 24 is a rear elevation view of FIG. 21;

FIG. 25 is a left side elevation view of FIG. 21;

FIG. 26 is a right side elevation view of FIG. 21;

FIG. 27 is a top plan view of FIG. 21;

(Continued)

FIG. 28 is a bottom plan view of FIG. 21;
 FIG. 29 is a front, right and top perspective view of the Lid 3 and Barrel of the montessori toy set of FIG. 1;
 FIG. 30 is a front, right and top perspective view of the Lid 3 of the montessori toy set;
 FIG. 31 is a rear, left and bottom perspective view of FIG. 30;
 FIG. 32 is a front elevation view of FIG. 30;
 FIG. 33 is a rear elevation view of FIG. 30;
 FIG. 34 is a left side elevation view of FIG. 30;
 FIG. 35 is a right-side elevation view of FIG. 30;
 FIG. 36 is a top plan view of FIG. 30; and,
 FIG. 37 is a bottom plan view of FIG. 30.
